UNITED STATES PATENT OFFICE

FRANK E. STAHL, OF TONAWANDA, NEW YORK, ASSIGNOR TO COLUMBUS MCKINNON CHAIN CORPORATION, OF TONAWANDA, NEW YORK, A CORPORATION OF NEW YORK

ATTACHMENT FOR CHAIN MAKING MACHINES

Application filed March 18, 1931. Serial No. 523,522.

This invention relates generally to machines for forming chains and particularly to a machine for forming a chain from wire specially shaped in cross section for use in anti-skid tire chains.

The object of the invention is more especially to provide means in such a machine whereby in the series fed to the link former the short link forming wire pieces—called link blanks—are alternately turned on their axes so as to change their relative positions circumferentially prior to their presentation to the link forming devices as hereinafter explained. For example in manufacturing a cross chain for an anti-skid device for a motor vehicle tire in which the cross chain is made up of links formed from wire having a sharp longitudinal edge along one side, such as shown and described in the United States Patent dated December 23, 1930, No. 1,786,818, it is desirable, if the sharp edges of the links are to face, in use, at the exposed side when on the tire so as to take a firm grip on the road or ice, that each of alternate pairs of link blanks be given approximately a quarter turn prior to its insertion through the next previously formed link.

The present invention, therefore, consists principally in the herein described and claimed means embodied in a chain making machine for giving such a turn to the pieces from which the links are formed.

Except as modified by my invention the wire feeding, cutting and link forming devices and mechanism for operating are substantially the same as in the corresponding type of link forming machine and therefore need not be described in great detail.

In the accompanying drawings illustrating one embodiment of the invention—

Figure 1 is a top plan view of a link forming machine according to the present invention.

Fig. 2 is a detail on a larger scale of the mechanism for actuating the wire rocking means, said mechanism appearing at the left hand end of Fig. 1.

Fig. 3 is an elevation partly in section on the line III—III Fig. 2 looking to the left.

Fig. 4 is a detail in plan view on a larger

scale than in Fig. 1 of the wire shearing and rocking devices.

Fig. 5 is a detail in elevation and section on the line V—V Fig. 4 of the wire rocking devices.

Referring to the drawings the wire 10 is drawn from a reel (not shown) through straightening rollers 11 by means of an ordinary clamping device 12 on the end of lever arm 13, the latter being oscillated on the fulcrum point 15 by means of a cam 14. On the cam 14 is a cam 17 that operates a lever 16 fulcrumed at 19 and grips wire 10 thereby preventing said wire 10 from being carried back by the return stroke of lever 13. The wire 10 is fed into shear holder 22 the required distance through hardened holder 21 that is rigidly held in a fixed block 20, said shear holder 22 being rigidly held in a block 23 that is fastened to a slide 24^a that operates the bending fingers 24 for forming chain links around a mandrel 24^b.

When slide 24^a moves forward the wire stock is sheared off at the point 25 to the required length between the holders 21 and 22. Said sheared-off portion shown at 10^a in the holder 22, is then oscillated on its axis by means of an oscillating holder 26. Ordinarily the locating head 27 has the internal passage shaped to fit the form of wire with a bevel at the entering end 28.

Attached to the oscillating holder 26 is a lever 29, one end of which contains a roller 30 that is held in a slotted fork 31 on the end of a piston 32 sliding in housing 33, the latter being fastened to the top guide 34 by means of screws 35. At the end of piston 32 and housing 33 are located screws 11^a and 12^a adjustable to limit the travel of piston 32 in one direction. 15^a designates a plunger stop, the end of which is moved into and out of the housing 33 by means of a lever 16^a fastened to shaft 31^a crossing below and held in suitable bearings in the bed 17^a of the former and timer bracket 19^a. The timer bracket 19^a is mounted on the side of a bed 17^a between cam wheels 20^a and 21^a that operate the turning fingers and mandrel respectively. On one end of shaft 31^a is mounted timer lever 22^a which carries two pivoted arms 23^a each of which

has a roller 24^a attached to its free end. On the other end of lever 22^a is a bolt 25^a that slides in a slot in the end of a lever 26^a fulcrumed on the bracket 19^a by means of bolt 27^a. Between the end of lever 22^a and 26^a is stretched a tension spring 28^a which governs the position of lever 22^a. Bolted fixedly to the sides of the rotating cam wheels 20^a and 21^a are dogs 30^a.

During one rotation of the cam wheels 20^a and 21^a two links are formed, but during this rotation the timer lever 22^a is fixed in the position towards cam wheel 20^a as shown. In this operation the plunger 15^a is carried below piston housing 33 thereby allowing the piston 32 to travel up against stop screws 12^a under the action of spring 13^a. The piston 32 carries lever 29 forward into the position shown in Fig. 5 and said lever 29 turns holder 26 with locating head 27 that has carried the stock into correct position for feeding the link blank into position ready to be formed on the mandrel.

At the end of the revolution of cam wheel 20^a the dog 30^a rises under roller 24^a and carries it upward through the lost motion range until roller arm 23^a makes contact with the lever 22^a, the lever 22^a being carried by spring 28^a over toward cam wheel 21^a going a little beyond the vertical towards cam wheel 21^a against stop screws 29^a.

This operation also permits the plunger 15^a to rise into the piston housing 33 to hold the piston against movement by the spring. While the lever 22^a has been changing its position the cut off slide 23 has been in the forward position with piston 32 in the forward position in housing 33. When the slide 23 returns the piston 32 contacts with the stop plunger 15^a by means of stop screws 11^a. As the slide 23 continues to move the lever 29 is thrown over into the opposite position and carries the link blank into the next forming position where it remains for one revolution of cam wheel 21^a after which the holder 27 is returned to the original position and the operation repeated.

From the foregoing it will be observed that the full line position, Fig. 5, represents the block 23 in wire feeding position. When said block is moved from the full line position to broken line position the wire is cut to form the link blank, the pin 23^b on the block supporting the arm 29 and holding it in the same relation to said block 23. When the pin 15^a is moved up to stop the piston 32 and the block 23 is returned with the cut blank in the rocking holder 26 to wire feeding position the arm 29 of the rocking holder is swung to the right on its pivot in the fork at 31 thereby imparting a turn to the rocking blank holder and to the wire blank therein. From this position it is fed to the link formers as before stated.

In the construction shown it will be noted that after two link blanks are turned and

upon the next two cutting movements of the block 23 the pin 15^a is not elevated to arrest the piston 32, hence the block and link blank therein are each returned to blank feeding position without rocking the holder 26 and the cut blank therein. Hence pairs of the link blanks are fed to the link formers with their sharp edges out of line or in endwise angular relation to each other. In practice the ends of the links can be subsequently welded in a welding machine and after the links are welded they are subjected to the twisting operation so that the sharp edges of the faces of the links are all on one side of the chain and in substantially the position and relation to one another as shown in said Letters Patent No. 1,786,318 hereinbefore referred to.

The forms of the parts can be changed without departing from the gist of the invention as claimed.

What I claim is:

1. The combination in a chain making machine having a wire stock feeding means, means for shearing the stock into link blanks, link forming means and means for turning alternate blanks on their axes prior to their presentation to the link forming means.

2. The combination in a chain making machine having a wire stock feeding means, means for shearing the stock into link blanks, link forming means and means for turning the alternate blanks on their axes prior to their presentation to the link forming means, said last named means consisting of a holder from which the link blanks are protruded to the link forming means, and cam actuated means for rocking said holder.

3. The combination in a chain making machine having a wire stock feeding means, means for shearing the stock into link blanks, link forming means and means for turning the alternate link blanks on their axes prior to their presentation to the link forming means, said last named means consisting of a holder from which the link blanks are protruded to the link forming means, and cam actuated means for rocking said holder, said cam actuated means operable with alternate operations of the link forming means.

4. The combination in a chain making machine having wire stock feeding means, link forming means, a holder for receiving a link blank prior to its presentation to the link forming means, and means for rocking said holder on its axis to rock the link blank therein.

5. The combination in a chain making machine having wire stock feeding means, link forming means, a holder for receiving in succession link blanks each prior to its presentation to the link forming means, and means for rocking said holder on its axis to rock alternate link blanks supplied to said holder.

6. The combination in a chain making ma-

chine having a wire stock feeding means, means for shearing the fed stock into link blanks including a sliding block, a link blank holder in said sliding block, means for rocking said holder, and means for causing the intermittent actuation of said rocking means to change the position of alternate link blanks circumferentially.

7. The combination in a chain making machine having a wire stock feeding means, means for shearing the fed stock into link blanks including a sliding block, a link blank holder in said block, rocking means for said holder to change the position circumferentially of alternate link blanks supplied to said holder and means for timing the operation of said rocking means.

8. The combination in a chain making machine having a wire stock feeding means, means for shearing the fed stock into link blanks including a sliding block, a link blank holder in said block, rocking means for said holder to change the position of alternate link blanks supplied to said holder and means for timing the operation of said rocking means to change the position circumferentially in said holder of alternate link blanks supplied to said holder.

9. The combination in a chain making machine having a wire stock feeding means, means for shearing the fed stock into link blanks including a sliding block, a link blank holder in said block, rocking means for said holder to change the position of alternate link blanks supplied to said holder in forming the chain and means for timing the operation of said rocking means to change the position circumferentially in said holder of alternate link blanks supplied to said holder.

40 10. The combination in a chain making machine having a wire stock feeding means, means for shearing the fed stock into blanks including a sliding block, a link blank holder in said block, rocking means for said holder to change the position circumferentially of certain of said link blanks supplied to said holder in forming the chain and means for timing the operation of said rocking means.
